UNITED STATES PATENT OFFICE

142,997

DESIGN FOR A TEXTILE FABRIC

Daniel B. Fuller, New York, N. Y.

Application August 1, 1945, Serial No. 121,148

Term of patent 3½ years

(Cl. D92—1)

To all whom it may concern:

Be it known that I, Daniel B. Fuller, a citizen of the United States of America, residing in New York city, county of New York, and State of New York, have invented a new, original, and ornamental Design for a Textile Fabric, of which the following is a specification, reference being had to the accompanying drawing, forming part thereof, wherein the figure is a plan view of a

textile fabric showing my new design. The dot and dash lines on the drawing outline two design units. The unit is repeated in regular succession as indicated by the extensions beyond the unit boundaries.

I claim:

The ornamental design for a textile fabric, substantially as shown and described.

DANIEL B. FULLER.
